His Attorney.

UNITED STATES PATENT OFFICE

GEORGE H. TOVEY, OF SCHENECTADY, NEW YORK, ASSIGNOR TO GENERAL ELECTRIC COMPANY, A CORPORATION OF NEW YORK

CIRCUIT CONNECTER

Application filed May 18, 1925. Serial No. 30,935.

My invention relates to electrical apparatus wherein a terminal member or connection is carried through and supported by a wall which may be, for example, the cover of an oil switch tank or the like. An object of my invention is to provide an improved apparatus of this character which shall be simple in construction, effective in use and inexpensive to manufacture.

My invention will be better understood from the following description taken in connection with the accompanying drawing, and its scope will be pointed out in the appended claims.

Figure 1 shows in partial section an oil switch and terminal, illustrating one embodiment of my invention; Fig. 2 is a perspective view of the terminal alone, and Fig. 3 is a detail of the same.

For the purpose of illustration I have shown my invention as forming a part of an oil circuit breaker or switch comprising the movable contact or bridging member 1, the operating rod 2 therefor and the stationary contact member 3. The contacts are immersed in oil contained in the tank 4 provided with the cover 5. Through suitable openings in the cover extend the two terminal members 6 by means of which external circuit connections are made with the stationary switch contacts 3. Each terminal member 6 comprises a tube 7 of conducting material, preferably copper, whose ends 8 and 9 are flattened to form flat contact faces. The switch contact 3 is shown secured by screws 10 to the lower contact face 9 and the connector 11 is shown secured by the bolt 12 to the upper contact face 8. For the greater part of its length, the tube is covered with insulation 14 which may be molded or wrapped on the tube or may simply be formed in tubes, cut to length and slipped on the conducting tube.

For securing the terminal firmly to the cover 5 and in a position to bring the contact 2 at the proper height, I have provided a clamping member 15 which may be in two parts but preferably in one piece as illustrated. This member has a flange portion 16 which is bolted or otherwise secured to the cover 5 and a sleeve portion 17 which tightly

clamps the insulated portion of the tube. I preferably make the clamping member 15 of a size that it may be slipped over the tube and the insulation to the proper position and then by the suitable application of pressure contract the sleeve portion 17 until a permanent deformation is formed in both the insulation and the walls of the tube. By this means the terminal member may be firmly secured to the cover of the switch tank without the use of additional insulation and in a position to bring the stationary contact member at the proper height for engagement with the movable contact member of the switch.

What I claim as new and desire to secure by Letters Patent of the United States, is:

1. In combination, a supporting member, a terminal member comprising a conducting tube extending through said supporting member, insulation surrounding and engaging the tube, and means for securing said terminal member to said supporting member comprising a ring surrounding the insulation on the tube and contracted to deform both the tube and the insulation thereon.

2. A terminal member comprising a conducting tube having its ends flattened to form contact faces, insulation fitting an intermediate portion thereof, said tube and insulation having corresponding deformations and a securing member for the tube comprising a ring surrounding the insulated portion thereof, said ring engaging in the deformations in the insulation and the tube.

3. In combination, an electric switch having an enclosing casing, a terminal for said switch comprising a tube of conducting material extending through a wall of the casing, a yielding insulating sleeve surrounding and engaging the tube, and a member for securing the tube to the casing comprising a flange portion arranged to be fixed to the casing wall and a sleeve portion, said conducting tube and insulating sleeve having therein corresponding annular depressions and the sleeve portion of said securing member firmly engaging in said depressions.

4. An electric switch having an enclosing casing, a circuit terminal extending through the casing comprising a conductor tube hav-

ing an insulating tube thereon, and means for securing the tube to the casing comprising a member having a sleeve portion surrounding and contracted to deform the conducting tube and the insulating tube at corresponding points thereof and a flange portion attached to the casing.

In witness whereof, I have hereunto set my hand this 16th day of May, 1925.

10 **GEORGE H. TOVEY.**
